MASON HULETT, OF NEW YORK, N. Y., ASSIGNOR, BY MESNE ASSIGNMENTS, TO THE BURDICK CORPORATION, OF MILTON, WISCONSIN, A CORPORATION OF DELAWARE

MERCURY VAPOR LAMP

Application filed February 20, 1923. Serial No. 620,190.

In operating high pressure mercury vapor lamps, it is desirable to start the arc at as low as amperage as possible. For the type of lamp taking normally 3.5 to 4.0 amperes the lowest practicable starting amperage has been 8.0 to 10. This is due to the fact that when a lower starting amperage than what may be called the critical starting value inherent to this type of lamp is used the arc is established with difficulty and the build up period is materially lengthened. It may be said that a criterion for the critical starting value, is that current at which, when the lamp is started, the arc will be established promptly and will build up rapidly. The critical starting value has been universally accepted in practice to be from approximately 100% to as much as 200% in excess of the normal operating or stable current value.

My invention relates to an apparatus and a method whereby this type of lamp can be started at a relatively low amperage, and at the same time retain and even improve the build up characteristics as compared with the starting of the lamp under the high critical starting current method heretofore employed. In fact, my method enables me not only to start the lamp materially below the critical starting value but to obtain the normal operating values immediately following the formation of the arc. This I accomplish, in the particular apparatus shown, by heating the mercury electrode. The heating of the mercury causes vapor to form and build up pressure in the bulb of the tube which results in the lowering of the mercury level in the bulb and the raising of the level in the body of the tube until the mercury contacts with the anode. I have observed that there is a slight oscillation of the mercury in the body of the tube and that, immediately after this contact, the mercury recedes and breaks contact with the anode, thus striking an arc therebetween. Consequently with my method it is not necessary to tilt the tube to strike the arc, as is now the common practice.

Another feature of my improved method and apparatus consists in automatically starting the lamp again when the main operating current fails to flow therein. The means for

accomplishing this result comprises a circuit in shunt to the lamp containing the heating means, which circuit is opened and closed by means of an automatic switch actuated by current flowing in the lamp circuit.

The foregoing objects are attained by the arrangements illustrated in the accompanying drawing in which

Fig. 1 shows a vapor electric lamp provided with a mercury cathode and a hot anode;

Fig. 2 illustrates a slightly modified form of apparatus for automatically cutting out resistance; and

Fig. 3 is a set of curves illustrating certain comparative results obtained by my invention.

Referring to the drawing in detail the reference numeral 10 designates a high pressure mercury vapor lamp of the hot anode type supported in an adjustable holder 11 so that the tube of the lamp may be located at a desired angle. 12 is a suitable heating coil of high resistance wire, 13 an automatic solenoid switch, and 14 the ballast resistance ordinary to this type of lamp. The operation is as follows: When the main switch 15 is closed the heating circuit becomes energized. Vapor soon forms in the bulb 16 of the lamp as well as in the tube. After a few seconds the mercury starts to boil with a result that the mercury level in the bulb falls with a consequent extending of the mercury body in the tube. As the heating continues the mercury body in the tube approaches the anode 17 until contact is made. The slight oscillation of the mercury column in the elongated body of tube 10, which I have heretofore mentioned, causes this contact to be broken immediately and this separation of the mercury from the anode draws and starts the arc.

As soon as the arc starts the switch 13 opens, breaking the contact 18 whereby the heating circuit is deenergized. Should the arc fail for any reason the switch 13 closes the contact 18 and the whole starting operation is immediately repeated.

It will be understood that when the starting amperage is limited by the amount of resistance in series with the lamp, the run-

ning or normal operating voltage of the lamp will be limited to a certain value. When it is desired to increase the voltage across the lamp, I short-circuit a portion of the resistance at a predetermined point in the build-up of the lamp. For automatically cutting out of resistance, I prefer to use a device as shown in Fig. 2. This device consists of two opposing coils 19 and 20 with cores of magnetic material adapted to attract the lever 21, which is also of magnetic material. Upon the comparatively high starting current, the pull of coil 20 is preponderant and the lever 21 is kept from closing upon contact 22. When the current falls to a predetermined value the pull of the coil 19 becomes preponderant, due to the difference in the reluctance of the magnetic circuits of these coils, and the lever 21 closes upon contact 22, shunting coil 20 and a portion of the resistance 14. Electromagnetic switches having the operating characteristics above described are well known in the art. United States Patent No. 1,825,049 granted December 16, 1919, illustrates one form of such a switch. It is readily appreciated that by the use of the mechanism just described, I am able to start the lamp at a desired low amperage and subsequently, if desired, increase the voltage to a higher value than that fixed by a current limiting resistance.

In the drawing I have illustrated the lamp as having been so adjusted that when the proper temperature of the mercury electrode has been reached the same will contact with and then separate from the other electrode and thereby form the arc. It will be readily understood, however, that my invention also contemplates the heating of the mercury electrode to the desired temperature and thereafter manually or automatically bringing the electrodes in contact.

I have found that the build-up characteristics of the lamp when started in the described manner can be varied by adjusting the position of the mercury in the lamp tube. This variation is shown in Fig. 3 where curves A show characteristic voltage and amperage curves when the lamp is started with the mercury body approximately one-half inch from the anode 17. Curves B show the characteristic voltage and amperage curves when the lamp is started with the mercury body approximately two inches from the anode 17.

The value and importance of this discovery is apparent by comparison of curves C and D in Fig. 3. Curves C show the characteristic build-up of a 110 volt lamp when operated in the ordinary manner with the starting current limited to 4.5 amperes. It is readily appreciated why such a starting characteristic is impossible for a lamp in commercial use. The arc is not established until eight minutes after being struck. Fur-

thermore, preceding the final establishment of the arc a violent play extending over a period of approximately two minutes takes place between the mercury and the anode which is extremely objectionable. The operating characteristics of the lamp do not reach a stable condition until sixteen minutes after the start.

Curves D show the characteristic build-up under the same conditions prevailing from which curves C are taken when the means I have described are employed. It will be noted that the arc is established in less than one minute after being struck. The establishment of the arc is smooth with no fluctuations or objectionable features such as prevailed in the previous illustration. The operating characteristics are practically normal two minutes after starting, no change taking place in the voltage and a difference of but 0.2 amperes showing in the current curve.

I have illustrated and described herein the improved and preferred form of apparatus for carrying out the method which I claim. It is to be expressly understood, however, that I do not limit myself thereto as changes may be made in points of detail and other embodiments resorted to without deviating from the true spirit and scope of my invention.

What I claim is:

1. The combination with a vapor lamp having two electrodes one of which is mercury, of an electrically actuated heater for heating the mercury electrode and thereby causing the same to approach the other electrode to establish contact therewith, a circuit for supplying current to the heater and the lamp electrodes, a relay for opening the circuit to the heater when contact is established between the electrodes, a resistance in the circuit for controlling the voltage impressed between the electrodes, and a relay in the circuit acting automatically to increase the voltage impressed between the electrodes when the current flowing therebetween falls to a predetermined value.

2. The combination with a vapor lamp having two electrodes one of which is mercury, of an electrically actuated heater for heating the mercury electrode and thereby causing the same to approach the other electrode to establish contact therewith, a circuit for supplying current to the heater and the lamp electrodes, a relay for opening the circuit to the heater when contact is established between the electrodes, a resistance in said circuit for controlling the voltage impressed between the electrodes, and a relay operable when the current between the electrodes falls to a predetermined value to reduce said resistance and thereby increase the voltage impressed between the electrodes.

3. The method of starting a vapor arc elec-

- tric lamp having a pair of main electrodes of which one is a vaporizable liquid, which consists in heating the liquid electrode below its surface to cause oscillations thereof toward and from the other electrode until the liquid momentarily contacts with the other electrode to start an arc therebetween, and automatically stopping the application of heat when the liquid contacts with the other electrode.
4. The method of starting a vapor arc electric lamp having a main cathode of mercury and a rigid anode, which consists in applying heat to the cathode to create vapor pressure below its surface to produce oscillations thereof toward and from the anode until the mercury momentarily contacts with the anode to initiate the flow of current and the striking of an arc therebetween, and automatically interrupting the application of heat to the cathode when the cathode contacts with the anode.
5. The combination with a vapor arc lamp having an evacuated envelope in the form of an elongated tube with a mercury cathode adjacent one end and a rigid anode spaced from the cathode of an electric heater associated with the mercury to impart heat thereto beneath its surface to create pressure behind the surface of the mercury to impel the same by a series of oscillations toward the anode, a circuit for supplying current to the heater, and means for interrupting the flow of current to the heater when the cathode contacts with the anode.

In testimony whereof, I have hereunto set my hand this 17th day of February, 1923.
